UNITED STATES PATENT OFFICE.

NORMAN L. SNOW, OF DETROIT, MICHIGAN, ASSIGNOR TO DIAMOND POWER SPECIALTY CORPORATION, OF DETROIT, MICHIGAN, A CORPORATION OF MICHIGAN.

BOILER CLEANER.

Original application filed January 15, 1923, Serial No. 612,864. Divided and this application filed July 13, 1925. Serial No. 43,301.

The invention relates to boiler cleaners and refers more particularly to boiler cleaners in which a discharge of a cleaning fluid such as steam is utilized to effect cleaning.

This application which is a division of my copending application Serial Number 612,864, filed January 15, 1923, further relates to an improved blower unit or element.

In the drawings:
10 Figure 1 is a sectional view of my blower element;

Figures 2, 3 and 4 are like views illustrating modifications; and

Figure 5 is a semi-diagrammatic sectional view through a typical boiler showing my blower element associated therewith.

Referring to the drawings showing my blower units, elements or pipes in Figures 1 to 4 inclusive, it will be noted that these 20 units while specifically different, possess in common the characteristic of a gradual reduction of diameter from the inlet to the opposed end of the unit. One of the main objects of thus constructing the units is 25 economy, it being the practice to form said units from metal having high heat resisting qualities such as nichrome, hardite, nickel, monel, etc. As all of these materials are rather costly, the saving resulting from the 30 gradual reduction in cross section instead of continuing the inlet passage of the units throughout their length is an important consideration. As shown, in Figure 1 the pipe 10 is formed at intervals with annular shoulders 11 whereby the diameter of successive 35 portions of the pipe is stepped down. 12 represents the cleaning fluid discharge nozzles.

Figure 2 discloses a similar construction 40 except for the fact that the successive portions are tapered rather than cylindrical.

As shown in Figure 3, the gradual reduction of diameter is accomplished by a continuous uniform taper.

45 Figure 4 discloses a construction differing from that of Figure 1 only in the respect that the adjoining stepped down portions have screw-threaded engagement instead of being integrally connected.

50 A further advantage of the form of blower pipe shown in Figures 1 to 4 inclusive lies in the fact that the tapered form facilitates

casting since by virtue of said form the pipe might be more readily removed from a mold.

In Figure 5 I have shown one of my blower pipes associated with a typical boiler, the same being designated generally by the reference character 13. As illustrated the blower pipe is adapted to extend transversely of the boiler tubes 14 and in this position is in the path of the furnace gases passing upwardly around the boiler tubes. By virtue of the gradual reduction in diameter of the pipe, less obstruction is presented to the flow of the furnace gases than is possible where the pipe is of the same diameter throughout its length and it therefore constitutes a further advantage of my invention that the element effects a diminution of the resistance to the flow of the furnace 70 gases.

What I claim as my invention is:—

1. A tubular blower element provided with a series of discharge nozzles distributed along its length for discharging a cleaning fluid adjacent parts of a boiler to be cleaned, said blower element diminishing in diameter from one of its ends to the other so that when operatively associated with the boiler the resistance to the flow of furnace gases 80 will be diminished.

2. A tubular blower element formed of a heat resisting alloy and provided with a series of discharge nozzles distributed along its length for discharging a cleaning fluid adjacent parts of a boiler to be cleaned, said blower element diminishing in diameter from one of its ends to the other so that when operatively associated with the boiler the resistance to the flow of furnace gases will be 90 diminished.

3. The combination with a boiler having a plurality of tubes, of a tubular blower element positioned within said boiler, said element being formed of a heat resisting alloy and provided with a series of discharge nozzles distributed along its length for discharging a cleaning fluid toward the boiler tubes for cleaning said tubes, said blower element diminishing in diameter from one 100 of its ends to the other.

In testimony whereof I affix my signature.

NORMAN L. SNOW.
